UNITED STATES PATENT OFFICE.

CHARLES ALLEN KARR, OF GREEN ELM, KANSAS.

HYDROSTATIC LEVELING-INSTRUMENT.

SPECIFICATION forming part of Letters Patent No. 375,450, dated December 27, 1887.

Application filed June 24, 1887. Serial No. 242,405. (No model.)

To all whom it may concern:

Be it known that I, CHARLES ALLEN KARR, a citizen of the United States, residing at Green Elm, in the county of Crawford and State 5 of Kansas, have invented a new and useful Improvement in Hydrostatic Balances, of which the following is a specification.

My invention relates to an improvement in hydrostatic leveling-instruments designed for 10 use in ascertaining the levels of planes of different heights, where it is impracticable, by reason of intervening obstructions or otherwise, to use the ordinary level; and my invention consists in the combination, with the 15 standards connected by a tube, of floats arranged in the said standards and adapted to serve as sights and also to serve as stoppers when the standards are overturned, to prevent the escape of liquid therefrom, as will be more 20 fully set forth hereinafter, and particularly pointed out in the claim.

In the accompanying drawings, Figure 1 is partly an elevation and partly a vertical sectional view of a hydrostatic leveling-instrument embodying my improvements. Fig. 2 25 is a transverse sectional view, taken on the line xx of Fig. 1.

M represents a pair of standards, each of which consists of a base, A, having an annular 30 recess, a , on its upper side, a metallic tube, B, having its lower edge secured in the said recess, a glass tube, C, arranged in the metallic tube, and a head, D, screwed into the upper end of the metallic tube, and effecting a water-tight joint with the upper edge of the glass 35 tube by means of a rubber or other suitable packing-ring, E. A similar packing-ring is also arranged between the lower end of the glass tube and the base. Each tube B is provided in one side with a vertical slot, b , on one side of which is a graduated scale, b' . Each 40 head D has a vertical central opening, d , and each base has a stop cock or valve, G, that communicates with the lower end of the glass 45 tube, as shown.

N represents a flexible tube, of sufficient strength and length, and which has its ends attached to the valves or stop-cocks G, thereby connecting the standards together. A suitable 50 quantity of water or other liquid is placed in the instrument as usual.

In each standard is a float, F, which is adapted to float on the column of liquid therein, and indicate the height of the said column of liquid on the graduated scale, as will be 55 readily understood. Air which enters the upper ends of the standards through the openings d presses upon the upper sides of the floats, and the latter are provided with suitable packing, which is rather loosely arranged 60 in the glass tubes to permit the escape of air from between the walls of the glass tubes and the sides of the float.

In using the instrument, the standards are placed in proper positions, the valves are 65 opened, and the liquid allowed to come to a level and raise the floats in the standards, to serve as sights, after which the valves are closed.

In the event that the standards should be 70 overturned, the pressure of the liquid therein will force the floats snugly against the heads D and effectually close the opening d , and thereby prevent the escape of liquid from the standards.

From the foregoing it will be understood 75 that my floats serve the purpose of sights when the instrument is in use and as stoppers to prevent the escape of liquid when the instrument is overturned, the said floats constituting the novel feature of my invention.

Having thus described my invention, I claim—

In a hydrostatic leveling-instrument, the standards having the air-inlet openings at 85 their upper ends, and the floats arranged in the standards and serving the purpose of sights, said floats being also adapted to close the openings in the upper ends of the standards and serve as stoppers to prevent the escape of liquid 90 therefrom when the instrument is overturned, substantially as described.

In testimony that I claim the foregoing as my own I have hereto affixed my signature in presence of two witnesses.

CHARLES ALLEN KARR.
